UNITED STATES PATENT OFFICE.

ROBERT W. SCOTT, OF BABYLON, NEW YORK.

WEB-HOLDER MECHANISM FOR KNITTING MACHINES.

Application filed April 9, 1920. Serial No. 372,387.

To all whom it may concern:

Be it known that I, ROBERT W. SCOTT, a citizen of the United States, and resident of Babylon, in the county of Suffolk and State of New York, have invented new and useful Improvements in Web-Holder Mechanism for Knitting Machines, of which the following is a specification.

This invention relates to web-holder mechanism, sometimes called sinker mechanism, for knitting machines.

The general purposes of such mechanism are to act upon the last knit course to feed the fabric away from the needles course by course as fast as it is knit; to provide stops against which a yarn of fabric loop on a relatively-moving knitting needle may abut, these stops serving in one direction of motion to define a point beyond which the previously-knit course may not be carried in the direction in which the knit loop is drawn by the needle-hook; and to hold down the knit web, as the needles rise.

In circular knitting machines the position and motion of the web-holders is radial; the construction of such machines implies arrangements by which the web-holders are held against movement in the direction of the length of the operating needles, and further necessitates arrangements by which the flat, thin web-holders can be prevented from tilting out of the planes normally occupied by them. No prior device of which I am aware is successful in attaining these results. The usual construction provides a radially-grooved web-holder dial or bed made as an annulus attached to the outside of the needle cylinder, an inner web-holder ring having a series of radial guide slots placed between the needle grooves, and a web-holder cam-ring mounted for rotative motion with respect to the web-holder bed to work the web-holders in their guides.

The vertical position of the web-holders is not accurately controlled by such structures ordinarily employed, and means have heretofore been proposed to increase the accuracy of this position of web-holders, such as providing that part of their grooved guiding means which lies within the position of the needles with means limiting the motion of a part of the web-holders vertically, either upwardly, or downwardly, or

both, the outer ends of the web-holders being prevented from much motion by the coaction of their supporting bed or dial and their actuating cam-ring.

When extremely fine gages are employed for the production of hosiery, frequently as fine as 24 needles to the inch, the depth of cutting of the inner grooved web-holder ring makes the partitions between the grooves so thin and so weak that the ordinary strains of knitting tend to bend these partitions, and consequently to throw the web-holders out of line with the knitting needles. This results in faults in the fabric, such as holes and unsightly lines. When attempt has been made to make these slots shallow, in order to make the partitions stronger, this has been done at the sacrifice of properly positioned bearing surfaces for the web-holder, the outwardly-distant web-holder cam ring having to serve as the means to retain the web-holders downward against the upward thrust of the needle.

This expedient is successful only when the parts are new, since the leverage of the upward thrust on the thin web-holder rapidly wears away the underside of its cam ring and the outer end of its bed groove. This wear is irregular and causes irregularity of length of the knit loops.

Other prior constructions of which I am aware have all either called for too deep cutting of slots, in order to accommodate a lower arm or finger on the web-holder which could be engaged within the line of needles and held down by a retaining ring, or have necessitated the provision within the needle cylinder and in the direction of the thrust of the web-holders of other types of retaining means, all characterized by closed pockets or bottoms in the line of the thrust of the web-holders which after operation for a little time become clogged with impacted lint, are difficult to clean, and result in irregularly limiting the inward thrust of the web-holders and uneven fabric, and often also result in broken partitions between grooves.

One principal object of the present invention is to provide a web-holder mechanism which will efficiently guide web-holders accurately spaced between the needles and accurately erect; which will provide easily-con-

structed accurate guiding surfaces coating with linear edges of the web-holder to position the web-holder accurately in respect to both the downward thrust and the upward thrust of the needles; which will prevent wear of the web-holder bearing surfaces; which will provide against accumulations of lint; which will provide means for resiliently controlling the motion of the web-holders; which will enable resilient holding of the needles at a relatively high point, and which will prevent the faults of inaccurate position, breakage and undue wear characteristic of the prior art.

15 In the accompanying drawings,—

Figure 1 is a diametrical section through a typical needle cylinder head, web-holder bed, web-holder cam ring and web-holder ring of a circular knitting machine, illustrating 20 one form of the invention;

Figure 2 is a plan view of the web-holder ring as shown in Fig. 1;

Figure 3 is an enlarged elevation of a preferred type of web-holder;

25 Figure 4 is an enlarged radial section of the web-holder ring shown in Figs. 1 and 2;

Figure 5 is an under plan view of one type of the web-holder cam ring;

Figure 6 is a detail elevation looking in 30 the direction of the arrow *a*, Fig. 5;

Figure 7 is a detail plan of a modified form of web-holder ring;

Figure 8 is an under plan view of the part shown in Fig. 7;

35 Figure 9 is a side elevation of the part shown in Figs. 7 and 8;

Figure 10 is a radial section on a larger scale, of a web-holder ring showing a further modification;

40 Figure 11 is a radial section through a web-holder groove of a further modification of the web-holder ring; and

Figure 12 is a detail plan, enlarged, of the form shown in Fig. 11.

45 Referring now to Fig. 1, the needle cylinder 1 may be externally grooved at 2 for any type of needle, and may be provided with any suitable means, such as the flange 3 cut through by the needle grooves 2, upon

50 which the web-holder bed 10 is tightly fitted. As usual in the art, the bed 10 is radially grooved at 11, the grooves being spaced between the needle grooves 2 in the assembled structure; the bed 10 may provide a bearing at 12 as usual for a depending annular flange 13 of the web-holder cam-ring 15 (Figs. 1 and 5), carrying the usual withdrawing cam 16 and advancing cams 17, 17, controlling the butts 21 of the web-holders

55 60 65 70 mounted in the grooves 11 of the bed 10. The usual circular groove 18 may limit the position of butts 21 except at the cams 16, 17, and the relative time of insertion of web-holders having longer butts may be controlled by a movable cam 19, as usual. A

parallel-faced radial slot 7 is formed through ring 15, except flange 13, at a place over a part of flange 13 strengthened by a lug 8, to receive a removable gate 9 formed with matching segments of flange 13 and groove 18. Removal of gate 9 permits access to or removal of the web-holders without disturbing the ring 15.

A preferred type of web-holder, as best

75 shown in Fig. 3, may consist of a parallel-faced flat piece of sheet metal having operat-

ing butt 21, a knocking-over surface 22, and a hold-down hook 23 defining a throat at 23^a

where it merges into surface 22. Preferably

80 the bottom edge 24 of the web-holder is straight except for a bevel at its inner end;

and the body of the web-holder may be di-

vided into an upper arm 25 and a lower arm

26, the bottom surface 27 of the upper arm

being straight and parallel with the bottom

85 24 of the web-holder, the upper surface 28 of

the lower arm 26 also being straight and par-

allel with the bottom 24 of the web-holder.

The slot 27, 28, between the arms 25, 26, ends

90 at 27^a at a substantial distance outwardly

from the throat 23^a, for instance so far as to

bring the throat 23^a over the middle of the

edge 27, for purposes presently explained.

The size, shape and dimensional relations be-

95 between the edges 27, 28, 24, the surface 22,

and the hook 23 may of course be accurately

100 the same throughout the series employed in

the machine, for uniform knitting. The up-

per arm 25 and the lower arm 26 may be re-

duced in thickness in a lateral sense, as for

example back to the line 29, as usual in the

art. The series of web-holders may include

any desired number having longer butts as

indicated by dotted lines at 21^a.

In modern knitting machines, where a

wide range of variation in the length of

stitch is desired, as between the tight knit

foot portion and the slackly-knit upper leg

portion, it is desirable that the web-hold-

ers shall be held resiliently inward, and for

110 this purpose I prefer to employ and endless-

coil spring band 30 completely encircling

the instruments and tending to force them

toward the center of the machine. Hereto-

fore, so far as I am aware, spring bands of

115 this nature have been used only with web-

holders of the type pivoted at their lower

ends, or at the outer ends of sliding web-

holders beyond their operating butts.

It will be understood that such a spring

is more effective when the amount of mo-

tion of the part controlled by it is larger

in proportion to the length of the spring,

and that therefore the spring band should

be placed as near the center of the machine

as possible. This is provided for in the

present invention by a recess 31 at the

shoulder 32 joining the upper and lower

arms, and well within the operating butts

of the web-holders, so that the band 30 when

105

110

115

120

125

130

seated in the recesses in the series of web-holders is housed between the series of web-holders and the inner face of ring 15, but has sufficient radial play between the 5 shoulder 32 and the inner edge of the ring 15 (Fig. 1). It will be observed, see Fig. 1, that the position of the spring-band 30 is such as to render it accessible for removal through the free space above the notches 10 31 and shoulders 32 of the assembled series of web-holders, the band lying wholly within the inner periphery of the web-holder cap 15. In the preferred form shown 15 the band and the operating butt exert their stress in line with the bearing surface 27 on one edge of the web-holder slot and the cam-contacting surfaces of the butts 21. Breakage of the band 30 is not likely to 20 damage the fragile web-holders, since the broken sections can not well leave the deep slot between ring 15 and the series of recesses 31. Such breakage will not prevent 25 operation, however, since the motion of the web-holders relied upon is positive, and the limits of their motion are controlled by 30 abutment flanges respectively of ring 15 and ring 35. The ring 15 may be cut away at 33 to provide room for the outward motion of the web-holders and their band, as 35 best shown in Fig. 5.

The vertical, lateral or fore-and-aft angular position of the knocking-over surfaces 22 of the web-holders 20 should not be subject to irregular change from wear or 40 displacement under the thrust of the descending needle. This invention takes care of this by means of a bearing 39 (Fig. 4) for the lower straight edge 27 of the upper arm 25 of the web-holder against downward thrusts on a machined, turned, or ground, and therefore accurate, surface of the web-holder ring 35 lying cross-wise of the direction of the thrust, at a point as 45 near the surface 22 as possible (to prevent lateral rocking), and preferably intersecting the series of needles.

The bearing 39 is substantially above the bottom edges 24 of the web-holders 20 and their bearing in their bed 10.

50 The web-holders 20 are prevented from rising with the upward thrust of the rising needles by a similar bearing 40 (Fig. 4) for the upper straight surface 28 of the lower arm 26 of the web-holder on an annular surface of the ring 35 extending from a point outside of the line defined by the needles to a point inside the line defined by the needles, and hence lying across the line of thrust. These arrangements, with 55 respect to turning moments which can affect the web-holders, place the centers of effort of turning forces within the bases respectively represented by the bearings 39 and 40, and hence are such as to prevent any 60 pivotal or rocking tendency of the web-

holders against any other bearing than that of the turned surfaces of ring 35, and therefore unequal wear of different parts of these surfaces in long use is prevented. Neither the web-holder bed 10 nor cam 70 ring 15 is relied upon for the fore and aft angular positions of the instruments.

The lateral positioning of the web-holders in spaced relation between the needles is effected by relatively shallow slots 46 in the upper edge of the ring 35 (Figs. 2 and 4). As will be plain from the drawing, these slots laterally position the upper arm 25 of the web-holder at a considerable distance above the lateral bearings for the main body 80 of the web-holders at the lower edge 24 of the web-holders afforded by the slots 11. The erect position of the web-holder, prevention of lateral wobbling, and relief of lateral bending strain on the ring partitions 85 are thus secured.

In the form of web-holder ring 35 shown in Figs. 1, 2 and 4, the ring 35 is made separate from the needle cylinder 1, being turned to a bearing fit within the cylinder 1 90 at surface 36 and having an exterior flange 37 to rest upon the turned upper edge of the needle cylinder, in which it may be fastened by the usual set screw 38 (Fig. 1).

The ring 35 is provided with a peripheral flange 45 having the turned parallel bearing surfaces 39 and 40 (Fig. 4). The surface 40 is one wall of an annular groove 41 extending well inwardly, for instance, as shown, beyond the bearing surface 36 defining the inner periphery of the needle cylinder. The bottom of the groove 41 constitutes a shoulder 42, against which the lower arm 26 of the web-holders 20 may abut to limit the extreme inward movement of the web-holders. When the web-holders are at their extreme inward position, as shown at the left-hand side of Fig. 1, the bottom 27^a of the slot 27, 28, between the arms 25, 26, 100 of the web-holder is still well outward of the edge of flange 45. This distance is sufficient when latch-needles are in use, to prevent a misplaced latch standing at right angles to its needle from collision with the bottom 27^a of the groove in the web-holders on the inward thrust of the web-holders. The open space between the bottom 27^a and the flange 45 is too wide to accumulate lint, 105 is not laterally closed by housing in a groove, and is moreover constantly cleared by the fanning action of the rapidly opening and closing latches of the advancing and retracting needles. Spring 30, being still further outward than slot-bottom 27^a, 110 is safely out of reach of the opening and closing latches.

The profile of the ring 35 may slope inwardly at conical surface 43, and have a turned surface 44 in line with the bottoms of the needle grooves. Peripheral flange 115

120

125

130

45 is radially milled through to form grooves 47 (Fig. 2) for the reception of the needles. The grooves 47 for the needles are relied upon to space the needles laterally 5 at a relatively high point in relation to the knocking-over surfaces 22.

It will be observed that the shallow positioning slots 46 for the upper arms 25 of the web-holders are formed in the triangular 10 upwardly extending edge of the ring 35 in metal of little cross section. These shallow slots 46 are preferably formed as usual by a milling operation. As well known to machinists, such thin milled slots are difficult 15 to make of uniform depth; I therefore prefer not to rely on the bottoms of the slots 46 for any part of the vertical positioning of the web-holder, and therefore I cut these slots out to a sloping line α at an angle to 20 the line α' of the surface 39 of flange 45 relied upon for the vertical position of the web-holder on the down-stroke of the needle. The metal cut through by the slots 46 is so thin vertically and radially of the ring that 25 such rings can be milled with accuracy without danger of bending the short, and therefore stiff, partitions between them by the clogging of the milling cutter. In use the partitions by their shortness and stiffness 30 resist lateral bending strains put upon the web-holders inserted in the slots.

Reliance upon the bottom 42 of groove 41 for restraining motion in one dimension of the web-holder would introduce defects in 35 operation if means were not provided to prevent accumulation of lint in the bottom of the slot. As illustrated in Figs. 1 and 4, constant clearance may be effected by providing openings into the bottom of the slot 40 42 in any desired manner; for instance, milling cuts 50 of less vertical height than the width of the slot 41 (Figs. 1 and 4), preferably flush with its bottom surface, may be formed (leaving integral bridges 51 in as 45 many places about the cylinder as may be desired) without disturbing the shoulders 42 against which the arms 26 of the web-holders may abut. If the bearings of the slot 41 opposite the bridges 51 should accumulate lint, 50 they may be cleaned by the insertion of a tool in the slots 50, but the air-currents moving through the slots 50 and the constant motion of the web-holders tend to keep this space clean without further aid.

55 As an illustration of one of the numerous alternative forms which the openings into the bottom of the slot 41 may take, I have shown in Figs. 7, 8 and 9 a construction in which a large number of shallow depressions 52 are formed through the flange 37 and surfaces 36 of the ring 35, such depressions 52 preferably being formed by a milling cutter and having their upper edges 53 (see Fig. 9) beneath the bearing surface 40 60 for the upward thrusts. Or, as shown in

Fig. 10, depressions of the type 52, 53, may be formed in a ring having the slots 50 only at the places of the bridges 51 between the slots 50, thus providing free clearance for lint at all parts of the bottom of the 70 groove 41.

Other variations of the cross-section of the ring 35 are permissible in connection with any of the remaining features of the ring. For instance, as illustrated in Fig. 11, the flange 45 may be extended outwardly to prolong the bearing surface for the lower edges 27 of the upper arms 25 of the web-holders 75 20 and to provide a recess 60 for a spring band 61 housed between the arms 25 and 26 of the web-holders, and available to hold the needles, such as 62, Fig. 12, inwardly against the bottoms of the needle-grooves 47. A needle thus positioned is supported laterally and inwardly at a point 80 very near the knocking-over surfaces 22 of the web-holders. This is especially useful in transferring, the spacing of the needles and the rigid support of their hooks for accurate contact with the transfer instrument being 85 thus made possible with thinner and more resilient needles, or with needles having greater bends out of true alignment, than can be secured by any other means of which I am aware. Support such as secured by the 90 band 61 is also highly desirable for use with two-part latchless needles, as indicated at 62 (Fig. 12), serving to hold the needle members together in working position.

What I claim is:

1. A knitting machine having therein needles, web-holders, and bearing means for supporting the web-holders against thrusts communicated to them in opposite directions by the needles acting through fabric 100 in contact with the needles and web-holders, said bearing means comprising surfaces severally lying across the directions of thrust and on both sides of the centers of effort thereof, whereby to prevent fore and aft 105 turning stresses upon the web-holder.

2. A knitting machine having therein a needle cylinder and needles, web-holders, a web-holder bed for guiding the lower edges of the web-holders and bearing means on 110 the needle cylinder for supporting the web-holders against a thrust communicated to them by the needles acting through fabric in contact with the needles and web-holders comprising a surface lying above the web-holder bed and across the direction of thrust and on both sides of the center of effort thereof, and extending between the needles.

3. A knitting machine having therein needles, a series of web-holders, and means for supporting the web-holders against thrusts communicated by needles acting through the fabric, comprising a ring fast on the needle cylinder having thereon a common bearing surface for all of the web- 115 120 125 130

- holders lying across the direction of thrust and on both sides of the center of effort thereof upon the web-holders.
4. A knitting machine having therein needles, web-holders, and means for supporting the web-holders against thrusts in different directions communicated to them by the needles acting through the fabric, comprising a web-holder ring having bearings for edges of the web-holders severally lying across the directions of the said thrusts and on each side of the center of effort thereof upon the web-holders.
5. A knitting machine having therein a needle-cylinder, needles, and a web-holder ring adapted to be held within the needles, said ring having a bearing surface for web-holders extending outwardly beyond the needles, in combination with web-holders, and means for actuating the web-holders.
6. A knitting machine having therein needles, web-holders, and means for supporting the web-holders against thrusts in different directions communicated to them by the needles acting through the fabric, comprising a web-holder ring having a flange penetrated by grooves for the needles and having plane faces adapted to form bearings for edges of the web-holders severally lying across the directions of said thrusts and on each side of the center of effort thereof upon the web-holders.
7. Web-holder mechanism having therein a web-holder ring and a series of web-holders, said ring having a peripherally projecting flange taking between arms of the web-holders and having plane bearing surfaces common to said series, respectively for said arms, and means contacting with the web-holders at places separated in the direction of the length of the web-holders from said bearing surfaces on said ring for spacing the web-holders laterally by coaction with one only of said arms.
8. Web-holder supporting and guiding means for knitting machines having therein means coacting with parts of web-holders to resist lateral rocking, comprising a ring having thereon groove partitions for laterally spacing the web-holders, a downward bearing surface for an edge of the web-holders extending across the line of resultant downward thrusts of the fabric adapted to coact with a lower edge of a web-holder at a point near the edge of the web-holder supporting the fabric, and a web-holder bed having grooves for guiding an edge of the web-holder substantially lower than said first-mentioned edge.
9. A web-holder ring for knitting machines having thereon a flange grooved for the reception of needles and having upper and lower bearing surfaces extending outwardly beyond the bottoms of the needle-grooves to resist downward and upward
- displacement of upper and lower arms of web-holders spaced between the needle-grooves.
10. A knitting machine having therein a needle-cylinder, needles, and a web-holder ring adapted to be held within the needles, said ring having a bearing surface for web-holders extending outwardly beyond the needles in combination with web-holders, means for actuating the web-holders, and means permitting release of lint tending to accumulate in the path of the web-holders.
11. A knitting machine having therein a needle-cylinder, needles, and a web-holder ring adapted to be held within the needles, said ring having a bearing surface for web-holders extending outwardly beyond the needles, web-holders, and means for actuating the web-holders, said ring being provided with openings giving free clearance for lint impelled by the operating stroke of the web-holders.
12. A web-holder ring for knitting machines having thereon means for laterally spacing and guiding web-holders, and means for vertically positioning the web-holders, comprising a peripheral groove in the ring having a bottom adapted to engage and limit inward motion of the web-holder, said ring having therein lint-clearance openings taking into said groove.
13. A web-holder ring for knitting machines having thereon a flange grooved for the reception of needles and having upper and lower bearing surfaces extending outwardly beyond the bottoms of the needle-grooves to resist downward and upward displacement of upper and lower arms of web-holders spaced between the needle-grooves, said ring having a peripheral groove, one wall of which is said lower bearing surface, and a limiting stop for inward motion of the web-holders.
14. A web-holder ring for knitting machines having thereon a peripheral flange affording a bearing against vertical thrusts for web-holders grooved to laterally space needles, in combination with a spring-band there encircling the needles at the vertical position of said flange.
15. A web-holder ring for knitting machines having thereon a peripheral bearing flange for web-holders grooved to laterally space needles, said flange having there in a recess to receive a spring-band there encircling the needles.
16. Web-holder mechanism for circular knitting machines, comprising a web-holder bed grooved for the reception of sliding web-holders, web-holders in said bed having operating butts and an outwardly-facing shoulder inward of said butts, and a camming for operating the web-holders having a withdrawing cam thereon, in combination with a resilient band seated between said

- shoulder and said cam-ring, said cam-ring being recessed to provide clearance for said band at the places of withdrawal of the web-holders.
- 5 17. A web-holder ring for knitting machines having thereon a peripheral flange with upper and lower machined surfaces adapted to guide edges of the web-holders, and with an upper edge cut through by 10 slots adapted to receive the web-holders, in combination with web-holders, the bottoms of said slots being spaced away from the bearing-edges of the web-holders bearing on the surface of said peripheral flange.
- 15 18. A web-holder for knitting machines having a lower straight sliding edge, and having an operating butt, a hold-down hook for the fabric, and a shoulder recessed to receive a spring-band lying between said 20 hook and said butt on the edge opposite to the sliding edge, whereby the band is accessible for removal when the web-holder is in use.
- 25 19. Web-holder mechanism for circular knitting machines, comprising a web-holder bed grooved for the reception of sliding web-holders, web-holders in said bed having operating butts on one edge and an outwardly facing shoulder inward of said butts 30 on said edge, and a cam cap for operating the web-holder having an interior opening larger than the periphery defined by the said shoulders of the respective web-holders, in combination with a resilient band 35 seated between said shoulder and said cam cap, and thereby being adapted to be removed through the space between the series of shoulders and the cam cap.
20. A web-holder having therein a slot having a closed bottom, said slot defining arms adapted to straddle a bearing member and having outward of the bottom of the slot a shoulder recessed to provide a seat for a spring band, and having outward of the spring band an operating butt, the operating butt and the seat for the band being on the same edge of the web-holder, whereby in use the web-holder may have a support and bearing on one edge, and may be operated by structures reacting with projections from 40 the other edge.
21. A web-holder having thereon a plurality of straight arms extending in the same direction, one of the said arms having an edge to serve as a bearing surface for support upon a bearing member, said arm having on its other edge and substantially above the middle of the bearing edge means to engage and hold the fabric.
22. Web-holder mechanism comprising a 45 cam ring having a groove for operating butts of web-holders and a depending flange, and a slot intersecting the ring and its groove and bridged by said flange, in combination with a gate having a segment of 50 the groove formed therein adapted to be removably held in said slot.

Signed by me at New York, N. Y., this 6th day of April, 1920.

ROBERT W. SCOTT.
